(57) **CLAIM**

The ornamental design for a television receiver, as shown and described.

DESCRIPTION

FIG. 1 is a rear perspective view of a television receiver showing our new design according to a first embodiment; FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and

FIG. 8 is an enlarged view of the claimed portion shown in FIG. 1;

FIG. 9 is an enlarged view of the claimed portion shown in FIG. 3;

FIG. 10 is an exploded rear perspective view thereof, showing a stand in broken lines to provide example environment;

FIG. 11 is another exploded rear perspective view thereof, showing a wall mount bracket and a portion of a wall in broken lines to provide example environment;

FIG. 12 is a rear perspective view of a television receiver showing our new design according to a second embodiment; FIG. 13 is a front elevation view thereof;

FIG. 14 is a rear elevation view thereof;

FIG. 15 is a left side elevation view thereof;

FIG. 16 is a right side elevation view thereof;

FIG. 17 is a top plan view thereof;

FIG. 18 is a bottom plan view thereof;

FIG. 19 is an enlarged view of the claimed portion shown in FIG. 12; and,

FIG. 20 is an enlarged view of the claimed portion shown in FIG. 14.

The dashed broken lines showing of a stand, a wall mount bracket, and a wall in FIGS. 10-11 illustrate example environment that forms no part of the claimed design. The remaining dashed broken lines in the figures illustrate portions of the television receiver that form no part of the

(Continued)

claimed design. The dot-dash broken lines in the drawings illustrate a boundary of the claimed design and form no part of the claimed design.
